Primary Examiner — Jack Reickel*Assistant Examiner* — Bobby W Jones, II(74) *Attorney, Agent, or Firm* — Mark Malek; Widerman Malek, PL(57) **CLAIM**

The ornamental design for a water filter as shown and described.

DESCRIPTION

FIG. 1 is a front perspective view of a water filter according to the present invention.

FIG. 2 is a top plan view of the water filter illustrated in FIG. 1.

FIG. 3 is a bottom plan view of the water filter illustrated in FIG. 1.

FIG. 4 is a front elevation view of the water filter illustrated in FIG. 1.

FIG. 5 is a rear perspective view of the water filter illustrated in FIG. 1.

FIG. 6 is a left side elevation view of the water filter illustrated in FIG. 1; and,

FIG. 7 is a right side elevation view of the water filter illustrated in FIG. 1.

The broken line showing of a water filter is included for the purpose of illustrating portions of the article and forms no part of the claimed design.

1 Claim, 7 Drawing Sheets(56)
